UNITED STATES PATENT OFFICE.

GEORGE M. HUBBARD, OF NEW HAVEN, CONNECTICUT, ASSIGNOR TO
W. & E. T. FITCH, OF SAME PLACE.

DESIGN FOR A CLASP FOR BELTS.

SPECIFICATION forming part of Design No. 21,063, dated September 22, 1891.

Application filed August 31, 1891. Serial No. 404,345. Term of patent 7 years.

To all whom it may concern:

Be it known that I, GEORGE M. HUBBARD, of New Haven, in the county of New Haven and State of Connecticut, have invented a new Design for a Clasp for Belts, (Case B;) and I do hereby declare the following, when taken in connection with accompanying drawings and the letters of reference marked thereon, to be a full, clear, and exact description of the same, and which said drawings constitute part of this specification, and represent, in—

Figure 1, a face view of the two parts together; Fig. 2, a face view of the eye part detached; Fig. 3, a face view of the hook part detached.

This invention relates to a design for clasps for securing belts around the body, the design consisting in the ornamentation of the hook-and-eye part of the clasp.

20 A represents the buckle or loop by which

the eye part is secured to the belt, and B the loop by which the hook part is secured to the belt. From the eye part is a projection representing a fleur-de-lis *a*, as seen in Fig. 2, and from the hook part B is a projection representing a bar *b*, as seen in Fig. 3, and which when together represent a fleur-de-lis with a transverse bar or band interlaced therewith, as seen in Fig. 1.

I claim—

30 The design for a clasp for belts, as described, and shown in the accompanying illustrations.

In testimony whereof I have signed this specification in the presence of two subscribing witnesses.

GEORGE M. HUBBARD.
